TOOL CARRIAGE RING FOR PIPE CLEANING
MACHINES

Robert A. J. Dawson, Houston, Tex.

Application July 6, 1948, Serial No. 37,124

6 Claims. (Cl. 15—104.04)

1

This invention pertains to split hollow driven shafts and more particularly to such a shaft adapted to carry the tools of a pipe cleaning machine.

Pipe cleaning machines of the general type here considered are well known, one form thereof being illustrated and described in U. S. Patent 1,611,920, granted December 28, 1926, to Frank Kinzbach. Such machines comprise a bearing annulus that is placed over the pipe to be cleaned and a tool carriage ring also placed around the pipe. The ring rotates about the pipe inside the bearing. Anti-friction means such as rollers may be placed between the ring and annulus. The ring is driven from a source of power which may be mounted on a crawler frame adapted to ride on top of the pipe and advance the whole machine automatically along the pipe.

In such a machine as just described, there exists the problem of getting the tool carriage ring and bearing annulus around the pipe. Either they must be slipped over one end of the pipe or they must be split to allow them to be put in position at a point between the ends of the pipe. The aforementioned Kinzbach patent is an example of the latter type of construction. This invention pertains to a split tool carriage ring.

It is necessary that the joints between the parts of the split annulus and ring be such as to accurately align the parts again after they have been separated to place them over the pipe. Also, the joints must not interfere with the bearing surfaces of the annulus and ring nor with the drive surface of the ring. It is relatively easy to provide suitable joints for the bearing annulus since it is on the outside and stationary. A suitable arrangement comprises a hinge at one joint and a lock bolt at the other, the annulus being divided into two parts along a diameter thereof. A similar construction is shown in the Kinzbach patent. The hinge serves to maintain axial alignment of the parts of the annulus even when they are separated. Some difficulty is met however in adapting the hinge type of joint to the tool carriage ring, as will appear hereinafter.

In order to reduce the weight and complexity of the rotating ring as much as possible, it is desirable to mount the rollers on the annulus and to provide the ring with a smooth track to run on the rollers. For like reason it is desirable to make the ring of less width than the annulus and to leave as little clearance as possible between the ring and the tool mounts carried by the ring. These circumstances plus the fact that

2

the rotating ring must be provided with a drive surface combine to increase the difficulty in providing a suitable hinge for the tool carriage ring. The hinge cannot extend directly beyond the outer diameter of the ring or it will interfere with the track or drive surface, whichever is of larger diameter. Nor can the hinge extend to one side of the ring beyond the outer diameter of the ring because of the width and clearance limitations. On the other hand a hinge of ordinary construction cannot be placed with its pivot axis inside the outer diameter of the ring without relieving the ring on either side of the hinge to leave room for the parts of the ring beyond the pivot axis to come together, and such a construction cannot be used because the track and drive surface must be of full diameter at all points and cannot be relieved. The problem was not solved by Kinzbach who resorted to a non-hinged construction as described in his patent.

It is the object of this invention to provide an improved joint for a tool carriage ring which will maintain alignment of the bearing and drive surfaces thereof and will not interfere with adjoining parts.

It is a further object of this invention to provide a hinge whose effective pivot axis is on or beyond the outer surfaces of the hinged members so that they need not be relieved to permit them to open yet which has no parts extending beyond the outer surfaces of the hinged members.

Another object of the invention is to provide a joint of the foregoing type that will be simple and inexpensive yet strong and highly accurate in its constraint of the motion of the parts, and which will be economical in operation both from the standpoint of maintenance and repair and operating time.

Other objects and advantages of the invention will appear from the following description thereof.

Briefly the invention comprises a pipe cleaning machine having a tool carriage ring split diametrically into two parts with a link of adjustable length pivotally connected at its ends to the two parts of the ring on opposite sides of and close to one of the breaks thereof. The link may take the form of two rods each having an eye at one end and threaded at the other with the threaded ends connected by a turnbuckle. Each pivotal connection may comprise a stub shaft projecting from one side of one part of the ring and a bearing formed by the eye on one end of the link. The other break of the ring is provided with any releasable fastening

means such as two ears on opposite halves of the ring held together by a bolt and nut. When it is desired to open the ring the bolt and nut at one side are removed and the link at the other side lengthened permitting the ring to swing open. The reverse operation closes the ring.

For a detailed description of a preferred embodiment of the invention reference will now be made to the accompanying drawings in which:

Figure 1 is a side elevation of a pipe cleaning machine in position upon a pipe to be cleaned, the machine being shown only in general outline sufficient to indicate the relation of the bearing annulus and tool carriage ring to the machine as a whole;

Figure 2 is a rear elevation of the annulus and ring showing them partially open;

Figure 3 is a perspective view of the ring; and

Figure 4 is a side view, partly in section, of a portion of the ring showing the details of the hinge.

Referring to Figure 1, there is shown the general outline of a pipe cleaning machine comprising a supporting frame 11 having four legs depending therefrom such as those shown at 12 and 13 within which are pivotally mounted crawler wheels such as those shown at 14 and 15. Disposed on top of the supporting frame 11 is a suitable source of motive power, such as a gasoline engine indicated generally on the drawing at 16.

Depending from the supporting frame 11 is a bearing annulus indicated generally at 17. The upper portion of the bearing annulus comprises two plates 18 and 19 fastened to the underside of the supporting frame 11 and held apart in fixed spaced relation by spacing rods not shown. The lower half of the bearing annulus comprises a similar pair of plates, 20 and 21, also held together by spacing rods not shown. The upper and lower portions of the bearing annulus are hinged together at one side at 22 and 23 and releasably fastened together at the other side by means not shown in Figure 1. The bearing annulus carries a plurality of rollers such as those shown at 24, 25, and 26. The rollers are rotatably mounted on shafts such as those shown at 27, 28, and 29, extending between the plates thereof. Each roller is provided with a pair of annular flanges such as those shown at 30 and 31 on roller 26.

Within the bearing annulus there is provided a tool carriage ring indicated generally on the drawing by the reference character 32. The tool carriage ring is made up of an upper pair of semi-circular plates 33 and 34, and a lower pair of semi-circular plates 35 and 36. The inner edges of the plates forming the tool carriage ring are welded to two semi-circular hoop-shaped plates 37 and 38. The upper and lower portions of the ring are pivotally connected together at one side and releasably fastened together at the other side but for clarity these means have not been shown on Figure 1.

Each of the plates forming the tool carriage ring is provided with an exterior annular flange such as that indicated at 39 on plate 33. These flanges extend outside the flanges 30 and 31 on the rollers of the bearing annulus, thereby holding the tool carriage ring in correct axial alignment with the bearing annulus. In between the flanges 39 the outer edges of the plates forming the tool carriage ring provide tracks which ride on the flanges 30 and 31 of the rollers in the bearing annulus. Held between the opposite

plates of the ring by spacers such as those shown at 40 and 41 are two semi-circular sprocket wheel segments 42 and 43. The diameter of the sprocket wheel is smaller than the diameter of the roller track. A drive chain 44 passes over the two halves of the sprocket wheel in the tool carriage ring and over a drive sprocket 45 driven by the motor 16. The tool carriage ring is provided with a plurality of axially extending rods such as the one indicated at 46 upon which tools, not shown, may be mounted.

Before the machine is placed in operation, the two halves of the bearing annulus and tool carriage ring are disconnected at one side and allowed to pivot about the hinges connecting them together at the other side. After the bearing annulus and tool carriage ring have been opened, the machine may be placed in position upon a pipe such as that indicated in dashed lines on the drawing at 47 with the crawler wheels resting on the top surface of the pipe. The bearing annulus and tool carriage ring may then be fastened together and the machine is ready for operation. The motor 16 acting through the drive sprocket 45, drive chain 44, and the sprocket wheel inside the tool carriage ring will cause the tool carriage ring to be rotated about the pipe 47 while riding on the rollers of the bearing annulus.

Referring to Figure 2, each of the plates constituting the bearing annulus and the tool carriage ring is provided with a projection such as those indicated at 50, 51, 52, and 53, in the case of the upper plates or an indentation such as those indicated at 54, 55, 56, and 57, in the case of the lower plates. These projections and indentations are mating when the bearing annulus and tool carriage ring are closed and cooperate to prevent relative sliding of the upper and lower parts thereof. At one side of the machine the joints between the upper and lower halves of the bearing annulus and tool carriage ring are provided with readily disassemblable connecting means comprising ears 58, 59, 60, and 61 which are apertured and adapted to be held together by means of bolts and nuts such as those indicated at 62 and 63. The joints at the other side of the bearing annulus and tool carriage ring are provided with hinges. The hinge 22 on the bearing annulus is of an ordinary type comprising an apertured ear 64 secured to plate 18 and a bearing pin 65 secured to plate 20. The hinge for the tool carriage ring is indicated generally at 66.

A pair of apertured ears 67 and 68 are provided on the bearing annulus and tool carriage ring respectively. When it is desired to remove the pipe cleaning machine from the pipe the tool carriage ring is turned until its hinge 66 is adjacent to hinge 22 of the bearing annulus. In this position a bolt such as that shown at 69 may be passed through the ears 67 and 68 and secured with a nut 70 to hold the tool carriage ring fixed in position with respect to the bearing annulus. This will keep the track on the tool carriage ring in proper alignment with the rollers of the bearing annulus even after the joints between the upper and lower part of the annulus and ring have been broken and the lower portion thereof allowed to hinge downwardly.

Figure 3 shows a face of the tool carriage ring opposite to that shown in Figure 2. From a comparison of Figure 3 with Figure 2 it will be seen that there is a duplication of elements on opposite faces of the tool carriage ring. Like parts on opposite faces have been given like reference numbers. As shown in Figure 3 the projections

on the plates forming the upper part of the ring that mesh with the indentations on the plates of the lower part of the ring are formed by spacer rods as shown at 51. Holes for the tool mounting rods 45 are indicated at 70, 71, and 72, being provided in threes to permit adjustment to pipes of different diameters.

Referring now to Figures 3 and 4 it will be seen that the hinge 66 comprises pins 73 and 74 screwed into plates 19 and 21 and welded as indicated at 75. These pins pass through the eyes in the heads 16 and 17 on the ends of rods 78 and 79, the heads on the pins engaging the shoulders provided by the counterbores of the eyes as shown at 80 to retain the heads of the rods in position against the plates 19 and 21 while permitting them to pivot about the pins. The opposite ends of the rods 78 and 79 are threaded and screwed into an interiorly threaded turnbuckle which is a hexagonal nut provided with a hole 82 therethrough into which a pin may be inserted to facilitate the turning thereof. Jam nuts 83 and 84 are provided for locking the turnbuckle in any desired adjusted position. The rods and the turnbuckle should be of such length that the link formed thereby can be extended until its length is at least equal to the sum of the distances between each of the two pivot pins and the outer edge of the adjacent joint between the two halves of the ring so that the two halves of the ring can pivot about the outer edge of the ring at the joint and swing all the way apart. As previously noted the hinge 66 is duplicated on opposite sides of the tool carriage ring. This provides a strong support preventing the two halves of the tool carriage ring from becoming axially misaligned while at the same time permitting the two halves to be hinged apart when the turnbuckle is released.

While a preferred embodiment of the invention has been illustrated and described it will be obvious that many modifications thereof can be made without departing from the spirit of the invention. Thus, while the ring has been described as being split diametrically into two halves, the ring could be split along radii that are not in alignment or along one or more chords or into more than two parts or in other ways so long as sufficient room were provided for the ring when open to pass over the pipe. It is intended to cover by Letters Patent all forms of the invention falling within the scope of the appended claims.

I claim:

1. In a machine for performing operations upon a cylindrical body such as a pipe or rod, said machine including normally concentric annular bearing and shaft members adapted to be placed around a cylindrical body, one of said members being provided with a plurality of rotatably mounted rollers disposed with their axes of rotation parallel to the common axis of the bearing and shaft and circumferentially spaced in a circle concentric with said common axis, the other member being provided with a smooth continuous outwardly facing cylindrical track engaging said rollers from inside said circle whereby said shaft and bearing are relatively rotatable about their common axis, said track member having a pair of annular smooth oppositely facing surfaces lying in planes perpendicular to said common axis adapted to engage the rollers to prevent relative axial movement of said shaft and bearing, each of said members being divided along surfaces transverse to the circumference.

thereof into two segments, and means for holding said segments together in their normal position comprising a pivotal connection at one division of each of said members and releasable fastening means at the other division of each of said members, the improvement according to which said pivotal connection on the track member comprises a doubly pivoted hinge lying wholly within the outer periphery of said track member, said hinge comprising two adjustable length links each pivotally connected at one end to one segment of said track member and at the other end to the other segment of said track member, the pivot axis of each link upon each segment being in alignment with the pivot axis of the other link upon the same segment and parallel to the pivot axis of the same link upon the other segment and to said common axis of the shaft and bearing, each of said pivotal connections of said links comprising a support fixed to one of said segments and connected with an end of one of said links, said support and end having engaged correlative concentric cylindrical surfaces whose mutual axis constitutes the pivot axis of the link connection, said links each comprising a pair of at least approximately aligned rods, the adjacent ends of said rods being oppositely threaded, and a coupling having oppositely threaded ends engaged with the threaded ends of the rods, the length of each of said links being adjustable by turning said coupling relative to said rods between a retracted length at least as small as the distance between said pivot supports therefor when said segments are together in normal position and an extended length at least equal to the sum of the distances between each of the supports for the link and the outer edge of the adjacent line of division of the track member, said hinge positively preventing any relative motion of said segments when said segments are together in normal position and said links are adjusted to retracted length, and when said links are adjusted to extended length constraining the segments to relative motion only parallel to planes perpendicular to said common axis, the last said motion including rotation about an axis lying not closer to the common axis than the periphery of said track member and of sufficient extent to provide an opening between the ends of the segments large enough to pass over the side of said cylindrical body while maintaining axial alignment of said segments.

2. In a machine for performing operations upon a cylindrical body such as a pipe or rod, said machine including normally concentric annular bearing, shaft, and drive members adapted to be placed around a cylindrical body, said drive member having a smaller outer diameter than the largest diameter of the three members and being positively secured to said shaft, said bearing being provided with a plurality of rotatably mounted rollers disposed with their axes of rotation parallel to the common axis of the three members and circumferentially spaced in a circle concentric with said common axis, said shaft being provided with a smooth continuous outwardly facing cylindrical track engaging said rollers from inside said circle whereby said shaft and bearing are relatively rotatable about their common axis, said shaft having a pair of annular smooth oppositely facing surfaces lying in planes perpendicular to said common axis adapted to engage the rollers to prevent relative axial movement of said shaft and bearing, each of said members being divided along surfaces transverse to the circumference.

to the circumference thereof into two segments, and means for holding said segments together in their normal position comprising a pivotal connection at one division of each of said bearing and shaft and releasable fastening means at the other division of each of said bearing and shaft, the improvement according to which said pivotal connection on the shaft comprises a doubly pivoted hinge lying wholly within the outer periphery of said shaft, said hinge comprising two adjustable length links each pivotally connected at one end to one segment of said shaft and at the other end to the other segment of said shaft, the pivot axis of each link upon each segment being in alignment with the pivot axis of the other link upon the same segment and parallel to the pivot axis of the same link upon the other segment and to said common axis of the shaft and bearing, each of said pivotal connections of said links comprising a support fixed to one of said segments and connected with an end of one of said links, said support and end having engaged correlative concentric cylindrical surfaces whose mutual axis constitutes the pivot axis of the connection, said links each comprising a pair of at least approximately aligned rods, the adjacent ends of said rods being oppositely threaded, and a coupling having oppositely threaded ends engaged with the threaded ends of the rods, the length of each of said links being adjustable by turning said coupling relative to said rods between a retracted length at least as small as the distance between said pivot supports therefor when said segments are together in normal position and an extended length at least equal to the sum of the distances between each of the supports for the link and the outer edge of the adjacent line of division of the shaft, said hinge positively preventing any relative motion of said segments when said segments are together in normal position and said links are adjusted to retracted length, and when said links are adjusted to extended length constraining the segments to relative motion only parallel to planes perpendicular to said common axis, the last said motion including rotation about an axis lying not closer to the common axis than the periphery of said shaft and of sufficient extent to provide an opening between the ends of the segments large enough to pass over the side of said cylindrical body while maintaining axial alignment of said segments.

3. An extensible hinge comprising two members having correlative end surfaces adapted to make surface contact with each other, a pair of links each pivotally connected at one end to a side surface of one of said members and at the other end to a side surface of the other of said members, the pivot axis of each link upon each member being aligned with the pivot axis of the other link upon the same member and parallel to the pivot axis of the same link upon the other member, each of said pivotal connections comprising a support fixed to one of said members and connected with an end of one of said links, said support and end having engaged correlative concentric cylindrical surfaces whose mutual axis constitutes the pivot axis of the connection, said links each comprising a pair of at least approximately aligned rods, the adjacent ends of said rods being oppositely threaded, and a coupling having oppositely threaded ends engaged with the threaded ends of the rods, the length of each of said links being adjustable by turning said coupling relative to said rods over

a range between a short length causing said correlative surfaces to come into tight contact and a long length in which said surfaces are separated, the links and their connections to said members being disposed out of the path of travel of said surfaces between said separated and contacting positions leaving said path free and clear of all obstructions.

4. A ring divided diametrically into two halves 10 having coplanar ends, the two halves being connected together at one division point by a pair of links of adjustable length, means permanently pivotally connecting each link at one end to one half and at the other end to the other half, said 15 pivotal connections on each half having aligned pivot axes parallel to the pivot axes of the connections on the other half and to the ring axis, said pivotal connections constraining the links and halves to relative motion about said axes, 20 each of said links being extensible to a length at least equal to the sum of the distances from each of the pivot axes at the ends thereof to the outer edge of the adjacent line of division of the ring, the two halves being provided at 25 their ends opposite said one division point with releasable fastening means, said two halves of the ring being further provided at their joining coplanar surfaces with interlocking means for preventing relative displacement of the two halves in a direction transverse to the axis of the ring when the two halves are joined together.

5. In combination, a bearing annulus, an annular shaft concentrically supported by the inner periphery of the bearing annulus and constrained 30 thereby to rotation inside the bearing about the common axis, cooperating flange means on said bearing annulus and annular shaft for preventing relative axial motion thereof, each of said shaft and annulus being a full closed circular member, each of said members being divided 35 into two parts, the two parts of each of said members being hingedly connected together at one side and releasably fastened together at the other side, and means independent of the surfaces of said bearing annulus and annular shaft 40 that are in contact when said shaft rotates on said bearing for fixedly securing one part of said annulus to one part of said shaft when said shaft is rotated into a position relative to said bearing annulus in which said hinges are adjacent each other, whereby axial displacement of said shaft relative to said bearing annulus is prevented when said parts are unfastened and 45 swung apart upon their hinges, said securing means being releasable without unhinging of said parts.

6. A ring divided into two arcuate sections, the two sections being connected together at one division point by a pair of links, each link being 50 pivotally connected at one end to one section by means of a closed eye surrounding a pivot pin, said eye and pin members being disposed one member on the section and the other member on the link, each of said links being connected 55 in like manner at the other end to the other section, said pivoted connections on each section having aligned pivot axes parallel to the pivot axes of the connections on the other section and to the ring axis, said pivoted connections constraining the links and sections to relative motion about the axes of said pivot pins, means to adjust the length of each of said links over a range between a short length in which the two sections are held tightly together in a ring and an extended length at least equal to the sum of the

distances between each of the pivot pins therefor and the outer edge of the adjacent line of division of the ring, the two sections being provided at their ends opposite said one division point with releasable fastening means, and means comprising at least a portion of the junction surfaces of said sections at one, at least, of the division points of said ring and another such portion transversely disposed relative thereto for preventing relative displacement of the two sections in a direction transverse to the axis of the ring when the two sections are secured together by said links and said fastening means.

ROBERT A. J. DAWSON.
